UNITED STATES PATENT OFFICE

DAVID C. KLAUSMEYER, OF CINCINNATI, OHIO, ASSIGNOR TO THE CINCINNATI BICK-FORD TOOL COMPANY, OF CINCINNATI, OHIO, A CORPORATION OF OHIO

RADIAL DRILL WITH ALL CHANGE GEARS CENTRALIZED IN HEAD

Application filed February 19, 1924, Serial No. 693,945. Renewed February 12, 1926.

This invention relates to radial drilling and tapping machines and more particularly to the speed controlling mechanism for the spindles thereof.

Machine tools of this character are usually constructed with a base, an upright column, and a laterally projecting arm upon which the drill-head is adjustably mounted. Power to rotate the drill spindle and to feed it vertically is usually provided by a motor or other prime-mover located on the base at the foot of the column, and the power therefrom is transmitted through suitable mechanism to a shaft journaled lengthwise of the radial 15 arm and thence through suitable change-gear mechanism to the drill spindle.

As is well understood by those skilled in the art, it is essential that means be provided for regulating the speed of rotation of the 20 drill spindle inasmuch as the varying diameters of the drills and taps and the nature of the work being operated on, each present working-conditions which require different speeds of rotation of the spindle to produce 25 maximum efficiency in operation.

To provide these various speeds it has heretofore been customary to locate, adjacent the prime-mover, a change-gear mechanism capable of transmitting about six different 30 speeds from a single speed received from the prime-mover. The differences in ratio afforded by this so-called "speed-box" control are necessarily small since there is considerable mechanism actuated thereby and great 35 differences in ratio would effect abrupt changes and cause strains that would be detrimental to the parts.

Coarser changes are provided by a change-gear mechanism located in the drill-head. 40 These latter change-gears are known as the "back-gears" and usually provide four speed changes which multiply the speeds provided by the speed-box into about twenty-four speeds in the spindle. Inasmuch as only the 45 spindle is actuated by the back-gears the speed changes provided therein may be materially greater than those provided in the speed box.

Another well-known way of providing the 50 necessary number of spindle speeds is to re-

place the single-speed prime-mover and the speed-box with a variable speed motor capable of being operated at a plurality of speeds similar to the speeds produced in other machines by the speed-box, and combining therewith the usual back-gears in the drill-head.

To effect a predetermined speed in the spindle it has heretofore been necessary for the operator first, by the manipulation of certain control levers carried by the drill-head, to shift the back-gears and thereby obtain the nearest approximate speed obtainable therein; and second, to leave his position at his work and go to the opposite end of the machine where, by the manipulation of the speed-box control lever, or the motor controller whichever the case may be, effect the finer and more accurate speed setting. This remote location of the finer change-gears 70 makes their frequent manipulation inconvenient and unhandy and therefore the tendency of the attendant is to ignore the finer speed settings and to rely on the nearest speed obtainable in the back-gears which he may shift 75 from his position at his work which necessarily reduces efficiency.

This invention has for an object to combine entirely within the drill head, a plurality of sets of speed changing devices operative in conjunction with the usual back-gears to produce twenty-four speeds in the spindle from a single speed in the drive shaft.

A further object of the invention is to provide an improved form of gear shifting mechanism for selectively engaging the gears of the speed-change mechanisms.

A still further object is to provide improved means for maintaining the gears in their adjusted positions.

Another object of this invention is so to arrange the gears of the initial speed change device that, by simple movements of the shifting lever, the gears may be meshed in a pre-determined order to progressively increase or decrease the speed, whereby each speed attained will be only slightly greater or less than the preceding speed, thus precluding the clashing of fast and slow running gears.

Still another object of this invention is so

55

to arrange, in the drill head, the change gear sets for producing the twenty-four speeds from a single speed prime-mover, that, if desired, the initial speed change gears may be eliminated and the drill-head may readily be converted for use in conjunction with a variable speed motor and the back-gears only and still obtain the same results as is obtained with the single speed motor, the speed-box, and the back-gears.

These and other objects are attained by combining in the drill-head three independent speed-change devices of which the first two provide six speed changes and correspond to the usual speed-box control, and the third, which is the usual back-gears, provides four speed-changes, thus providing twenty-four speed-changes in the spindle.

A single control lever is provided for shifting the gears of the first and second gear-sets. This lever is mounted so as to be capable of universal movements and is so connected with the shiftable unit of each set that a movement in a vertical plane will shift the gears of one set and a movement in a horizontal plane will shift the gears of the other set. Independent shifting levers are provided for the shiftable units of the back-gears. Spring detents are arranged to engage the gear shifting devices whereby the levers, and thereby the gear-units, are held in adjusted positions.

To provide for the use of either a constant speed motor or a variable speed motor, the shaft supporting the driving gear-unit of the first gear-set is arranged co-axially with the shaft supporting the driving gear of the back-gear set so that, when desired, a single shaft may be inserted in place of the two independent shafts and the back gears thus connected directly with the drive shaft. With this arrangement the first and second gear-sets are eliminated, the variable speed motor providing the initial speed-changes. This is a highly important and desirable feature from the standpoint of manufacture as it permits the machine tool to be constructed completely with the exception of the motor and the change-gear devices, either form of which may be supplied later to meet the varying demands of the trade.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a vertical section of a drill-head embodying the present invention. Fig. 2 is a

detail section substantially on the line 2—2 of Fig. 1 but showing certain parts thereabove in elevation. Fig. 3 is a left-end view of Fig. 2. Fig. 4 is a diagrammatic representation of the flow of motion through the speed change mechanism. Fig. 5 is a detail view of detent means, later to be referred to, for holding the gear units in adjusted positions. Fig. 6 is a view similar to Fig. 1 but showing the drill-head equipped for use in conjunction with a variable speed motor. Fig. 7 is a detail section showing a modified arrangement of certain of the gears of the initial speed-change mechanism. Fig. 8 is a detail view of the speed index as used in conjunction with the gear arrangement shown in Fig. 7.

Referring more particularly to the drawings, especially to Figs. 1 and 4, power from a prime-mover, which may be a single speed motor, is (through suitable mechanism not shown) transmitted to a shaft 1 journaled lengthwise of the usual radial arm. From the shaft 1 the power flows to an upright shaft *a* journaled, by means of anti-friction bearings in bearing bosses 1° and 1^l, in the drill head *h*, suitable bevel gears represented generally by *x* serving to operatively connect the two shafts. Either of two bevel gears on the shaft 1 (one only of which is shown) may be meshed with the bevel gear on the shaft *a* to drive the shaft in reverse directions, but as this feature forms no part of the present invention detailed illustration and description thereof is deemed unnecessary.

Upon the shaft *a* is splined a gear unit 2 providing gears A, B and C adapted to mesh respectively with gears A', B' and C' comprising a gear-unit 3, loosely journaled on a shaft *b* fixed within bosses 1^b in the drill head, parallel with the shaft *a*. These gear-units 2 and 3 constitute a first speed-change device X (see Fig. 4) which provides three speeds from a single speed shaft 1 (hereinafter termed the power-shaft). A gear-unit 4 is also loosely journaled on the shaft *b* and is clutched at 5 to turn with the gear-unit 3. The gear-unit 4 provides gears D and E adapted to mesh respectively with gears D' and E' formed on a shiftable gear-unit 6. These gear-units 4 and 6 constitute a second speed-change device Y which doubles the three speeds available in the unit 3. The gear-unit 6 is splined upon a shaft *c* journaled co-axially with the shaft *a* in bearing bosses 1° and 1^l in the drill head. These shafts *a* and *c* being arranged co-axially may be replaced by a single shaft as will later be explained.

Splined upon the shaft *c* is a gear unit 7 constituting the first of a series of gears Z commonly known as the "back-gears" which operatively connects the six speed shaft *c* with the drill-spindle and multiplies its six speeds four-fold, thus providing twenty-four spindle speeds. The gear-unit 7 comprises gears F and G adapted selectively to be

shifted into mesh with gears F' and G' , respectively, provided by a gear-unit 8, keyed to a shaft d , journaled at one end in a bearing 1° in the drill-head and at the other end in a bearing s formed co-axially in the shaft b . The driven gear F' also acts as a driver and meshes with a gear H provided by a gear-unit 9 splined upon a sleeve 10, which in turn is splined to the drill spindle 11 in the usual manner. The shaft d is provided with a pinion I maintained constantly in mesh with a large gear I' forming a part of a gear-unit 12 loosely journaled upon the sleeve 10 and provided with an internal gear H' . The gear-unit 12 may be operatively connected with the spindle-sleeve by shifting the gear H downwardly into mesh with the internal gear H' .

The gear-units 2 and 6 are adapted to be shifted lengthwise of their supporting shafts to engage the gear-units 3 and 4 respectively, by a single mechanism now to be described. Within bearings 13 and 14, provided by the drill head, is slidably and rotatably mounted a shaft 15 upon which is secured a rack 16. A gear-shifting member 17, in the form of a bell crank lever, is pivoted at 18 in the drill head and carries at one end a shoe 19 adapted to track an annular groove 20 in the unit 6. The opposite arm of the bell-crank is formed as a gear-segment which meshes with the rack 16. Thus it will be seen that endwise movement of the shaft 15 will, through the rack 16, bell-crank lever 17, and shoe 19, shift the gear-unit 6 lengthwise of the shaft c . Upon a bushing, journaled within the bearing 14 and keyed to the shaft 15, is secured the hub of an arm 21 which carries a shoe 22 adapted to engage an annular groove 23 formed in the gear-unit 2. This arm 21 is formed with an arcuate sector 24 provided with a plurality of indentations i which cooperate with a spring pressed detent plunger 25 slidably mounted in the frame of the drill-head to maintain the arm 21 and the gear-unit 2 in adjusted position. Means to rotate the shaft 15 to shift the gear-unit 2, and to move it endwise to shift the gear-unit 6, preferably comprises a hand-lever 26 pivoted at 27 to the shaft, and carrying intermediate its ends a roller 28 which, when the lever is moved vertically slides between walls w provided by a bearing bracket 29 supported by the drill-head.

Upon movement of the hand lever 26 horizontally the walls w hold the roller 28 against movement and the lever fulcrums about the pivot 30 thus moving the shaft 15 lengthwise and shifting the gear-unit 2.

To aid the attendant in securing any desired setting of the gear sets X and Y the bracket 29 is provided with two indexes, m and n , and the shaft 15 carries an indicator finger o . The indexes m and n are located in different vertical planes corresponding to

the planes in which the finger o moves in either of the two lengthwise adjusted positions of the shaft 15. Thus the operator may, by manipulating the hand-lever 26, shift the gear-sets X and Y to secure any one of the six speeds indicated by the indexes m and n . 70

The gear-units 7 and 9 are adapted to be shifted by rock-arms 31 and 32 respectively secured upon pins 33 and 34 secured in the frame of the drill head. These arms engage the gear-units 7 and 9 in a well-known manner and suitable actuating levers (not shown) are secured to the shafts 33 and 34 outside of the drill head and afford means for manually shifting the gears. 75

The bell-crank lever 17 and the arms 31 and 32 are each provided at its outer end with a sector g within which is formed indentations k which cooperate with spring pressed detents 35 slidably fitted within cavities 36 provided by the drill-head frame. As these sectors and detents are all similar only one is shown in detail (see Fig. 6). 80

For certain purposes it may be desirable to have the gears of the initial gear set arranged as illustrated in Fig. 7. With this arrangement the highest speed is obtained by shifting the lever 26 to its uppermost position and then shifting it horizontally to move the shaft 15 inwardly. This will connect the gears $C-C'$ and $E-E'$ thus effecting a 1-to-1 drive between the shaft a and the shaft c , all connected gears being equal. In this position the indicator finger o will be in the position 1 on Fig. 8, this representing the highest speed obtainable in the first two gear-sets. The next lower speed is obtained by moving the lever horizontally to move the shaft 15 to the left as viewed in Fig. 1. This movement causes the rack 16 to swing the bell-crank and shift the gear D' into mesh with the gear D , the indicator finger having been moved outwardly to the numeral 2 on the index m . Alternate vertical and horizontal movements of the lever 26 will produce a gradual decrease of speed until the position 6 (Fig. 8) is reached in which the gears $A-A'$ and $D-D'$ are in mesh thus producing the lowest speed drive between the shaft a and the shaft c . 90

Referring now to Fig. 6 the drill head is shown equipped for use with a variable speed motor which produces the finer speed changes. When the drill-head is fitted in this manner a single shaft 40 replaces the shafts a , b and c and the gear-sets X and Y and connects the power shaft 1 with the first of the back-gears. This shaft 40 is journaled at its upper end in the bearing 1° provided by the drill-head frame and at its lower end in an anti-friction bearing fitted in the bearing-boss 1° ; passing centrally through the bearing boss 1° which in this arrangement performs no function. Inasmuch as the initial speed changes are effected by a variable speed motor connected 105 110 115 120 125 130

with the shaft 1 the shaft *b* and gear-units 3, 4 and 6 may be omitted and the shaft *d* may be journaled at its lower end in a bushing 41 carried by the bearing boss 1^b. Likewise 5 the shifting means for the gear-units 2 and 6 may be eliminated.

The co-axial arrangement of the bearings for the pairs of shafts is of great importance as it permits, first, a compact arrangement, 10 in a limited space, of a plurality of gear sets capable of producing twenty-four spindle speeds and second, it permits the same frame to be fitted, without change with the alternate arrangement shown in Fig. 6 and therefore 15 the manufacturer may, without added expense produce a drill head which he may later fit in either of two different ways to meet the varying demands of the trade.

Without further analysis, the foregoing 20 will so fully reveal the gist of this invention that others can, by applying current knowledge, readily adapt it for various utilizations by retaining one or more of the features that, from the standpoint of the prior art, fairly 25 constitute essential characteristics of either the generic or specific aspects of this invention, and, therefore, such adaptations should be, and are intended to be, comprehended within the meaning and range of equivalency 30 of the following claims.

Having thus revealed this invention, I claim as new and desire to secure the following combinations and elements, or equivalents thereof, by Letters Patent of the United States:

35 1. A drilling machine combining a drill-head; a power shaft; a sleeve journaled in said drill-head; a spindle splined to said sleeve; a second shaft journaled in said drill-head and operatively connected with said power shaft; speed-change mechanism carried within said drill-head for operatively connecting said second shaft with said sleeve, said mechanism including a third shaft secured in said drill-head parallel with said 40 second shaft, a fourth shaft journaled in said drill-head co-axially with said second shaft, a fifth shaft journaled within said drill-head co-axially with said third shaft, a change-gear set carried by said second and third 45 shafts, a second change-gear set carried by said third and fourth shafts and operatively connected with said first gear set, and a back-gear set operatively connecting said fourth shaft with said sleeve, said back-gear set comprising gear-units secured upon said fourth and fifth shafts and said sleeve; and means for meshing the gears of said gear-sets.

50 2. A drilling machine combining a drill-head; a power shaft; a second shaft journaled in said drill-head and operatively connected with said power shaft; a first gear-unit shiftably secured to said second shaft; a third shaft carried by said drill-head parallel with said second shaft; a second gear-unit loosely journaled on said third shaft,

said first and second gear-units together constituting a first speed-change device providing three speed changes; a third gear-unit loosely journaled on said third shaft and clutched to said second-gear-unit; a fourth shaft journaled co-axially with said second shaft; a fourth gear-unit shiftably secured upon said fourth shaft and adapted to be meshed with said third gear-unit, said third and fourth gear-units, 70 constituting a second speed-change device for doubling the speeds received from the first speed-change device; a fifth shaft journaled co-axially with said third shaft; a sleeve journaled in said drill-head; a spindle splined to said sleeve; gear-units on said fourth and fifth shafts and said sleeve for rotating said spindle from said fourth shaft, said last-named gear-units 75 constituting a third speed-change device for multiplying the speeds received from said second speed change device; and means for meshing the gears of said speed changing devices.

3. A drilling machine combining a drill-head; a power shaft; a second shaft journaled in said drill-head and operatively connected with said power shaft; a gear-unit splined to said second shaft; a third shaft parallel with said second shaft; a fourth shaft parallel with said third shaft; a first gear-unit journaled on said third shaft and adapted to mesh with the gear-unit on said second shaft; a second gear-unit journaled on said third shaft and clutched to said first gear-unit thereon; a gear-unit shiftably secured to said fourth shaft and adapted to be meshed with the second gear-unit on said third shaft; a spindle journaled in said drill-head; operative connections between said spindle and said fourth shaft for rotating the former from the latter; and a single gear-shifting lever carried by said drill-head and operatively connected to the gear-units on said second and fourth shafts for selectively shifting the gears thereof into mesh with the gears of the first and second gear-units on the third shaft.

4. A drilling machine combining a drill-head, a power shaft; a spindle rotatably journaled in said drill-head; means for rotating said spindle from said power shaft at varying speeds, said means including a plurality of shafts and first, second, and third change-gear devices each including a shiftable and a non-shiftable gear-unit; a single shifting mechanism for shifting the gears of said first and second change-gear devices, said shifting mechanism comprising a slide-shaft translatable and rotatably journaled in said drill-head; a rack secured to said shaft; a gear shifting bell-crank lever fulcrumed on a pin secured in the drill-head and having one arm provided with a gear-segment engaging said rack and the other arm provided with a fork engaging the shiftable gear-unit of said second change-gear device; an arm 120

splined to said slide-shaft; a fork carried by said arm and engaging the shiftable gear-unit on the second shaft; and a hand-lever secured to said slide shaft and movable in a vertical plane to rotate said shaft to shift one of said gear-units and in a horizontal plane to shift another of said gear-units.

5. The combination set forth in claim 4 characterized by this the arm of the gear-shifting bell-crank lever that is connected with the sliding gear-unit on the fourth shaft and the arm splined to the slide-shaft and carrying a fork engaging the sliding gear-unit of the second shaft, are each provided 10 with a segmental extension containing a plurality of identations which cooperate with a spring detent slidably mounted in the drill-head frame to maintain the gear-shifting arms and thereby the gear-units in their adjusted positions.

6. A drilling machine, combining a drill head; a power shaft; a spindle; means for rotating said spindle from said power shaft; a plurality of speed change devices for regulating the speed of rotation of said spindle each comprising a shiftable gear-unit and a non-shiftable gear-unit provided with gears of varying diameters; means for shifting said translatable gear-units comprising a rotatable slide-shaft; a single hand-lever connected with said shaft for rotating the shaft and sliding it endwise; means actuated by the rotary motion for shifting one of said gear-units; means actuated by the sliding movement of said shaft for shifting another of said gear-units; an indicator finger carried by said slide-shaft; an index cooperating with the finger in each of the lengthwise adjusted positions of said slide-shaft, said indexes each comprising indicia designating the speed obtained in any adjusted position of the hand-lever.

7. A drill-head combining a frame; a power shaft; a first series of three aligned bearings formed in said frame and arranged with their axes intersecting the axis of the power shaft; two shafts removably journaled in said three bearings; a driving connection between one of said shafts and said power shaft; a second series of three aligned bearings formed in said frame and arranged with their axes parallel with the axes of said first series; a shaft removably secured in two of the last named series; a bearing formed coaxially in said last mentioned shaft; a shaft journaled at one end in the bearing in said shaft and at its other end in the third bearing of said second series; a sleeve journaled in the frame; a spindle splined in said sleeve; intermeshing speed-change gear-units carried by said sleeve and said shafts for operatively connecting said spindle with said power shaft; and means for selectively shifting certain of said gear-units.

8. A drill-head combining a casing; a

power shaft; two shafts journaled co-axially in said casing with their axes intersecting the axis of said power shaft; a driving connection between one of said shafts and said power shaft; a non-rotatable shaft secured in said casing parallel with said two co-axially arranged shafts; two speed-change devices operatively connecting one of said two co-axially arranged shafts with the other, said speed change devices comprising two connected gear-units loosely journaled on said non-rotatable shaft and a gear-unit on each of said two shafts adapted to be meshed with one of said two connected gear-units; a spindle journaled in said casing; a back-gear mechanism operatively connecting said spindle with said two speed change-devices; and means permitting the removal of said two co-axial shafts and said two speed-change devices and the substitution therefor of a single shaft for directly connecting said power shaft with said back gears.

9. A radial drill combining a drill-head; a spindle rotatably journaled therein; a single speed power shaft; three sets of speed change gears embodied in said drill-head to rotate said spindle at a plurality of speeds from a single speed in the power shaft; shafts upon which said gears are mounted; bearings in said drill head rotatably to support said shafts, said bearings, gears and shafts being arranged on only three parallel axes.

10. A drilling machine combining a drill-head; a power shaft; a second shaft journaled in said drill head and operatively connected with said power shaft; a third shaft parallel with said second shaft; a three-speed change-gear mechanism between said second and third shafts to give to said third shaft three speeds from a single speed in the power shaft; a fourth shaft co-axial with the second shaft; a two-speed change-gear mechanism between the third and fourth shafts to give to said fourth shaft six speeds from a single speed in the power shaft; a spindle rotatably journaled in said drill head; and a four-speed change-gear mechanism between the fourth shaft and the spindle to give to said spindle any one of twenty-four speeds.

11. A radial drill head comprising a casing; a spindle journaled therein; a power shaft; a plurality of vertically aligned bearing bosses formed integral with said casing; a set of back-gears operatively connected with said spindle; a plurality of shafts removably journaled in bearings provided by said bosses; a gear connection between one of said shafts and the power shaft, said gear connection including a driving bevel gear on the power shaft and a complementary driven bevel gear journaled in said casing and held therein against axial movement, said driven bevel gear also having a splined connection with one of said plurality of shafts; a plurality of speed change devices carried by said plu-

rality of shafts for delivering to said back-gears a plurality of speeds to be multiplied by said back-gears; and means permitting the removal of said plurality of shafts and speed change devices and the substitution therefor of a single shaft for directly connecting said driven bevel gear with the first gear-unit of said back gears.

12. A drilling machine combining a drill-head; a power shaft; three sets of bearing bosses formed in said drill head and arranged on three parallel vertical axes, of which one axis intersects the axis of said power shaft; a spindle rotatably journaled co-axial with one of said sets of bearings; a plurality of aligned shafts journaled in each of the other of said sets of bearings; a gear connection between one of said shafts and said power shaft; a plurality of sets of speed change gears carried by said shafts and operatively connecting said power shaft with said spindle; and means to mesh the gears of each set selectively to give to the spindle any one of a plurality of speeds from a single speed in the power shaft.

13. A radial drill-head comprising a casing; a spindle journaled therein; a power shaft; a gear on said power shaft; a complementary gear rotatably journaled in a bearing provided by the casing and driven by the first mentioned gear; a plurality of bearings provided by said casing; a set of back-gears within said casing and operatively connected with said spindle; and means permitting said head to be equipped with a plurality of speed change devices for operatively connecting the driven gear with said back-gears, said means including a plurality of shafts journaled in said bearings and change gears carried by said shafts, or to be equipped with a single shaft journaled in only certain ones of said bearings and directly connecting said driven gear with said back gears.

14. In a radial drill-head, in combination a rotatable spindle; a power-shaft; an operative connection between said power-shaft and said spindle including a plurality of change-gear devices each including a shiftable gear-unit; a single shifting mechanism for two of said gear-units, said shifting mechanism comprising a shaft rotatably and translatable journaled in said head; a gear shifter engaging each of said two gear-units; means actuated by the rotation of said shaft to actuate one of said gear shifters; means actuated by the axial movement of said shaft to actuate the other of said gear shifters; and a universally actuatable lever connected to said shaft and having a floating fulcrum on said drill-head to rotate and translate said shaft.

15. A drill head combining a casing; a first driven gear permanently journaled in said casing and formed with a splined bore; a plurality of bearing bosses (1^a and 1^b) fixedly supported by said casing with their axes in

alignment with the axis of said gear; a bearing provided by one of said bosses; a first driven shaft (a) having one end splined within said gear and its other end journaled in said bearing; a second shaft (b) having one end journaled in said bearing and its other end in a bearing provided by the other of said bearing bosses, said last named bearing having an open end to permit withdrawal of said second shaft; a second set of bearing bosses (1^b, 1^b and 1^c) provided by said casing and having their axes parallel with the axes of the first named bearings; a third shaft (b) having its opposite ends supported in two of said second set of bearing bosses; one end of the last named shaft being formed with a central bore affording a shaft bearing; a fourth shaft having one end journaled in the bearing provided by said third shaft and its other end journaled in a bearing provided by one of the second set of bearing bosses, the last named bearing having an open end to permit withdrawal of said fourth shaft therefrom; a spindle driving sleeve journaled in said casing; a first set of speed change gears mounted upon said first and third shafts; a second set of speed change gears supported by said third and second shafts; and a third set of speed change gears mounted upon said second and fourth shafts and said spindle driving sleeve.

16. A drill-head combining a casing; a spindle rotatably journaled therein; a driven bevel gear permanently journaled in said casing and formed with a central shaft-receiving aperture; a first set of bearings supported by said casing and arranged with their axes in alignment with the axis of said bevel gear, one of said bearings extending through an outer wall of said casing; first and third shafts, a and c, journaled in said bearings, one of said shafts having a splined driving connection with said bevel gear; a second set of aligned bearings provided by said casing, one of the bearings of said second set extending through an outer wall of said casing; second and fourth shafts, b and d, journaled in said second set of bearings; primary and secondary sets of speed change gears supported by the first, second and third shafts, a, b and c, adapted to transmit to the third shaft c a plurality of speeds from a single speed in the bevel gear; a back-gear mechanism connecting the third shaft c with a spindle; said first, second and third shafts, a, b and c and the speed change gears carried thereby being removably secured in said casing, said shafts being withdrawable therefrom through the bearings extending through the outer wall of the casing, by axial movement of said shafts.

In witness whereof, I hereunto subscribe my name.

DAVID C. KLAUSMEYER. 130
